COUPLING ARRANGEMENT FOR AMPLIFIERS
AND REPEATERSWalter van B. Roberts, Bronxville, N. Y., assignor
to Radio Corporation of America, a corporation
of Delaware

Application September 2, 1926, Serial No. 133,283

3 Claims. (Cl. 178—44)

The invention relates to couplings through which a large range of frequencies are ordinarily used. It relates more particularly to radio frequency amplifiers, but is not limited to the exact range of frequencies which are ordinarily understood to be included in the radio frequency range. It might be also applicable to audio frequencies or even lower.

It has been known in connection with ordinary coupling arrangements heretofore used which intercouple different elements of energy changing arrangements such as amplifiers, detectors, etc., used with oscillatory currents, that the particular couplings were always susceptible and responsive to one particular frequency which predominated over all of the others. This was due to the inherent characteristics of the coupling elements, particularly the relation between the capacity and the inductance of the circuits.

In a great many cases throughout the radio and electrical art there is a necessity for coupling between two or more circuits. These circuits are said to be coupled when an alternating current flowing in one produces an electromotive force in the other. The number of volts of electromotive force produced in either circuit per ampere in the other circuit is called the mutual impedance between the two circuits. This mutual impedance may be obtained in several different ways.

If the two circuits are coupled by means of a mutual inductance, sometimes called a transformer, the mutual impedance increases directly with the frequency. In many cases it is desirable that the mutual impedance between the circuits be independent of frequency or that it vary with frequency less rapidly than with the ordinary case of the mutual inductances.

The objects of this invention are to obtain means for controlling the variation of mutual impedance. It may be controlled in such a way that it will be made to vary in any desired manner with the frequency. The manner for doing this and other objects, some of which will be found to be obvious from, and are explained more precisely in connection with the annexed drawings and the specification.

In this drawing Fig. 1 shows a resistance coupling;

Fig. 2 shows the mutual inductance coupling;

Fig. 3 shows a capacitance coupling;

Fig. 4 shows a self-inductance coupling;

Fig. 5 shows modification of Fig. 3 and

Figs. 6 to 11 inclusive show modifications and adaptations of the improved coupling means.

In connection with Fig. 1, element 1 shows a resistance where the mutual impedance is simply equal to the resistance and hence is practically independent of frequency. In other words, the coupling values are constant regardless of the change in frequency.

2 and 3 of Fig. 2 show inter-coupled inductance coils. The terminals at the left may be connected to one circuit and the terminals at the right are connected to another circuit in a similar way as Fig. 1 may be connected. In this type of coupling, as explained before, the mutual impedance between these two circuits varies directly with the frequency so that with an increase of frequency an increase of coupling exists. Also difficulties arise from the fact that there are other elements entering into the system, such as distributed capacity which causes the curve defining a mutual inductance throughout a given range of frequencies to deviate from a straight line.

4 in Fig. 3 is a condenser used for coupling between two circuits. This type of coupling works just the opposite from the type shown in Fig. 2; that is, the mutual impedance, due to a condenser common to both circuits, increases directly as the wave length or varies as the reciprocal of the frequency.

5 in Fig. 4 shows a single inductance coil and is substantially the same type of coupling as is shown in Fig. 2, inasmuch as the magnitude of the mutual impedance varies directly as the frequency. This is what is commonly known as the auto-transformer arrangement.

6, 7 and 8 of Fig. 5 show respectively a capacity shunted by an inductance coil which is coupled to another inductance coil. This type of coupling can be made approximately equivalent to the type shown in Fig. 3 over moderate ranges of frequency, as the transformer is so designed with respect to the capacity as to make the mutual impedance vary inversely with the frequency over the desired range of frequencies.

Now, in many cases it is desirable that the mutual impedances between two circuits be independent of frequency, or that it vary with frequency less rapidly than in Figs. 2, 3, 4 and 5. It is usually impractical to use resistance coupling for this purpose as it introduces energy losses which are undesirable. My invention consists in the method of utilizing both inductive and capacitive coupling at the same time so that as the mutual impedance of one element decreases that of the other element increases and vice-versa. By proper choice of the relative magnitudes of the two coupling means, the total

5 mutual impedance may be made to stay as nearly constant as there is any need for over a range of frequencies, such as is used in what is commonly known as the "broadcast range" or that 10 range of frequencies commonly used between 200 and 600 meters.

If desired, the relative values of the two coupling means may be designed so that the total mutual impedance increases somewhat with the 10 frequency, but not so rapidly as the mutual impedance due to the simple inductive coupling. Fig. 6 shows, in the simplest form, this type of compound coupling in which 10 and 11 are mutual inductances connected through a common capacity 9. The intercoupled circuits may be connected to the right and left hand terminals respectively, as before. It is essential that the windings 10 and 11 be in opposite directions so that the voltages produced by the inductive and 20 capacitive couplings add to each other rather than to subtract from each other, which would be the case if an attempt was made to combine the arrangements shown in Figs. 3 and 4, to 25 make a coupling element consisting of a coil in series with a condenser. However, this last mentioned coupling combination is useful in wave traps and filters where it is desired that the mutual impedance vanish completely for some particular frequency.

30 Fig. 7 shows a method equivalent to Fig. 6, but having what is in some cases the advantage of no metallic interconnection between the coupled circuits. Here 12 and 13 represent intercoupled inductances and 14 and 15 are separate inductances 35 coupled in the same way with the exception that condenser 33 is shunted around the element 15.

Fig. 7 is the combination of Figs. 2 and 5. When the capacity is only indirectly connected by means of a transformer in one of the circuits, 40 the polarity of this transformer may be reversed so that a single coil can be used, as shown in Fig. 8. This is probably not so desirable, as the arrangement shown in Fig. 6 and the only advantage it has is that the paths for direct current are 45 nowhere interrupted, as they would be by the condenser 9 in Fig. 6. In this last figure the capacity 16 is shunted by an inductance which is coupled with the inductance 17. These two inductances must be arranged in the same way as 10 and 11 of 50 Fig. 6. 18 is the common mutual inductance which is the equivalent to the inter-coupled inductances 12 and 13 of Fig. 7.

In Fig. 9 this arrangement is adapted for use with an antenna and 19 and 21 are inter-coupled 55 inductances as in Fig. 6 and 20 is a capacity which is mutual to both circuits. At present several taps are usually provided on the antenna coil of receiving sets and it is quite noticeable that the tap which works best at short waves is not the 60 best one for long waves. The arrangement of Fig. 9 allows the use of the same tap for all wave lengths without noticeable difference in efficiency. Similarly in making radio frequency transformers to go between vacuum tubes, it is well known that 65 a simple primary coil, having the best number of windings for amplification at the middle of the wave length range, will have too few turns for the best results at one end of the range and too many turns for maximum results at the other end of the 70 range.

Fig. 10 shows the arrangement in Fig. 7 adapted to this purpose, but other arrangements are 75 equally possible, such as Fig. 6. Here 22 and 23 are inter-coupled inductances and 25 is an inductance which is coupled to its primary which is

shunted by the condenser 26. These inductances together with inductance 24 and capacity 27 make up the tuning arrangement for the grid of the input connections for the instrument desired to be coupled.

Still another use for compound coupling is in connection with continuously tunable radio frequency filters. The width of the band of frequencies passed by a simple filter depends upon the mutual reactance between sections so that as it is desired to select a band of frequencies some 10 kilocycles wide no matter what part of the spectrum of broadcast frequencies we are selecting from, it is desired to have a mutual impedance element whose value does not vary appreciably over the broadcast range. Fig. 11 shows a typical filter section using this type of coupling. This is an adaptation of the coupling arrangement shown in Fig. 6, where the transformer coils are coalesced with the rest of the inductances. Here 28 and 31 are adjustable condensers, one in each side of the two circuits. 29 and 30 are inductances associated as in Fig. 6 and 32 is the mutual capacity.

A source of radio frequency voltage E is conventionally shown connected across the input terminals of the filter, the source being a signal energy collecting means, or a preceding amplifier of collected signal energy, as is well known to those skilled in the prior art. Across the output 25 terminals of the filter is connected a load conventionally represented equal to the value of terminating resistances. This load has a resistance value correct for ensuring the proper uniform band pass selecting characteristic of the filter. 35 The selected currents flowing through the load may be utilized to operate translating devices in any of the usual ways well known to those skilled in the art of radio reception. The term "filter", as used heretofore, is understood to imply to those 40 skilled in the art, the mathematical relations between the filter element and, additionally, the inclusion and nature of the voltage source, as well as the output load or terminating resistance.

It will be understood that if in Fig. 9 or 10 the 45 resistances of the coils vary with frequency, as is usually the case, the compound coupling will not be designed for constant mutual impedance but will be so proportioned that the total mutual impedance increases with frequency to the extent desirable to keep pace with the increase of resistance. The values of resistances in two coupled circuits always determine the optimum values of the mutual impedance between the circuits. Care should therefore be taken to prevent 55 unnecessary effective resistances at any particular frequency.

While only one application has been specifically mentioned for the features disclosed by the above description, it is not desired that this invention 60 be so limited, but it is believed unnecessary to enumerate the different applications in which the invention might be used. This invention might be used in the coupling of audio frequency amplifiers as well as radio frequency amplifiers.

Having described my invention with the various modifications, I wish to be limited only by the scope of the following claims and not by the exact structure disclosed.

What I wish to claim is:

1. A compound coupling arrangement for providing an effective mutual impedance between two circuits that varies with frequency over a range of frequencies in a predetermined manner, comprising mutual inductance between se- 75

ries elements of said circuits in combination with mutual inductance between a series element in one of said circuits and an inductance connected in shunt to a condenser in series in the other of said circuits, said last named inductance and condenser elements being chosen to determine a natural frequency below the lowest frequency of the said range of frequencies.

2. In combination with a source of signal energy, a coupling network comprising a primary circuit consisting of a pair of inductors in series, a secondary circuit consisting of a pair of inductors arranged in series, each of the secondary inductors being magnetically coupled to an associated one of said primary inductors, a variable condenser connected across the secondary inductors and adapted to tune the latter over a given frequency range, one of said primary inductors transmitting high frequencies of said range most efficiently, and the other primary inductor transmitting low frequencies of the range most efficiently.

3. A compound coupling arrangement for coupling two circuits with a total effective mutual impedance that varies with frequency over a relatively wide range of frequencies in a predetermined manner comprising in combination a first coupling between said circuits arranged to provide an effective mutual impedance therebetween which increases as frequency increases, a second coupling between said circuits arranged to provide an effective mutual impedance therebetween which decreases as frequency increases, said second coupling comprising a series condenser in one of said circuits, a coil shunting said condenser and having sufficient inductance to make the resonant frequency of the combination of said coil and said condenser low compared to any frequency in said range, an inductive element in said other circuit, and mutual inductance between said coil and said element.
